UNITED STATES PATENT OFFICE.

FRANK O. SCOTT, OF MITTINEAGUE, MASSACHUSETTS, ASSIGNOR TO SOUTHWORTH COMPANY, OF MITTINEAGUE, MASSACHUSETTS, A CORPORATION OF MASSACHUSETTS.

PAPER MACHINE.

1,420,869.

Specification of Letters Patent. Patented June 27, 1922.

Application filed July 18, 1921. Serial No. 485,524.

To all whom it may concern:

Be it known that I, FRANK O. SCOTT, a citizen of the United States, and a resident of Mittineague, in the county of Hampden and State of Massachusetts, have invented 5 certain new and useful Improvements in Paper Machines, of which the following is a specification.

This invention relates to paper machines, 10 and particularly to a lay-boy construction whereby sheets cut from a traveling web of paper may be properly piled in stacks.

It is an object of the invention to produce an apparatus of the character described 15 which is simple mechanically, and efficient.

In the drawings which present an illustrated embodiment of the invention,

Figure 1 is an elevation of a lay-boy device adapted to be placed at the delivery end 20 of the paper machine,

Figure 2 is a cross-sectional elevation of a part thereof, and

Figure 3 is an enlarged detailed view of one of the links of the chain.

25 This device comprises a pair of frames 1 between and under which and transversely of the direction of delivery of the paper is a truck 2 having a table 3 upon which the paper 4 is to be piled. Suitable mechanism not

30 herein shown, and not forming a part of the invention, is provided for raising and lowering the table as the stacking or piling proceeds. Arranged across the two frames 1 are a plurality of lay-boy rolls 5, these rolls

35 having square portions 6 at one end, and gears 7 at the other. Mounted on the frames is a track 8 and a rack 9, one on one frame, and the other on the opposite frame. The lay-boy rolls travel around the frames in the

40 direction of the arrow in Figure 1. When moving horizontally along the top of the frames, they move without rotation until the rack 9 engages the gears 7, at which time the rolls revolve and lay the paper smoothly on 45 the pile.

Very considerable difficulty has been encountered in maintaining a proper alignment and synchrony in the operation of the lay-boy rolls. These rolls are usually of 50 considerable length rapidly rotated, and ordinarily rotated from one end only.

I have provided means whereby the two ends of each roll may be positively kept in exact alignment across the machine, and the difficulties heretofore encountered obviated. 55 This result I obtained by employing a pair of strong chains 10 stretched tightly about the rollers 11 and the sprockets 12 on each frame. The two sprockets 12 are mounted on a common shaft and driven by any suitable means. 60

The engagement of the chains with the two sprockets 12 is positive, exact, and does not vary through long periods of use.

In order to connect the chain with the lay-boy rolls I secure, as by brazing or welding, journals 13 to links 14 of the chain. These journals are arranged on exactly corresponding links of the two chains. The lay-boy rolls 5 are mounted in the journals 13. By 70 this construction, the parts being once in alignment, the troublesome difficulties of the prior art practice which occur through the lack of exact synchrony between the two ends of the lay-boy rolls are obviated, and a construction is provided which maintains the exactness of its operation through long periods of use without adjustment. 75

I claim as my invention:

1. In a lay-boy device for paper machines, 80 a frame, plurality of lay-boy rolls, tracks in the frame for the end of the rolls, a rack associated with one track, a gear on each of the rolls cooperating with the track, a pair of chains connecting the corresponding ends of 85 the lay-boy rolls, and pulleys for guiding the chains.

2. In apparatus of the class described, and in combination a pair of frame members, a pair of chains each associated with a frame 90 member, rollers supported in the frame and guiding the chains, a shaft sprocket for driving the chains, a series of journals mounted on links of the chain, and in alignment in pairs across the frames, rolls journaled in 95 said journals, a rack on one frame, a gear on each roll, engageable with the rack.

In witness whereof, I hereunto subscribe my name this 8th day of July, A. D., 1921.

FRANK O. SCOTT.
